PNEUMATIC DISPLACEMENT PUMP

James O. McMillan, Wichita, Kans., assignor of
one-fourth to A. G. W. Biddle, Skiatook, Okla.

Application December 10, 1936, Serial No. 115,106

23 Claims. (Cl. 103—246)

This invention relates to pumps and more particularly to those of the pneumatic displacement type, for example, those used in automatic water systems.

5 The principal objects of the present invention are to provide a more efficient and positive pump action in pumps of this type with a snap action in opening the valves of the pump; to prevent loss of pressure medium by submerging the 10 valves in the liquid being pumped; and to provide a pump mechanism which is of extremely rugged construction.

15 Other important objects of the invention are to provide proper filling of the pump cylinder; to provide a valve mechanism which is controlled through flow of the liquid being lifted and to provide a substantially continuous flow of liquid at the point of delivery.

20 In accomplishing these and other objects of the invention, I have provided improved details of structure, the preferred forms of which are illustrated in the accompanying drawings, wherein:

25 Fig. 1 is a vertical section through a well or cistern equipped with a pumping apparatus embodying the features of the present invention.

Fig. 2 is an enlarged vertical section through the pump cylinder, particularly illustrating the valve mechanism.

30 Fig. 3 is a vertical section similar to Fig. 2 illustrating the float actuation of the control valve which effects power application of the hydrostatic pressure of fluid in the delivery line to a motive power cylinder.

35 Fig. 4 is a vertical section through the upper pump head taken from the direction opposite that shown in Figs. 2 and 3 on the line 4—4, Fig. 5.

Fig. 5 is a plan view of the pump head particularly illustrating the arrangement of the flow, pressure medium, and exhaust lines.

40 Fig. 6 is a horizontal cross section on the line 6—6, Fig. 2.

Fig. 7 is a bottom horizontal cross section of the pump head on the line 7—7, Fig. 2.

Fig. 8 is a horizontal cross section on the line 45 8—8, Fig. 3.

Fig. 9 is an enlarged vertical cross section illustrating a modified form of control valve at the lower end of the pump cylinder.

50 Fig. 10 is a horizontal section on the line 10—10, Fig. 9.

Fig. 11 is a vertical section through a further modified form of pump showing its valve mechanism, and particularly illustrating float operation 55 of the control valve which effects power applica-

cation of the hydrostatic pressure of fluid in the delivery line to a motor piston.

Fig. 12 is a horizontal section on the line 12—12, Fig. 11, particularly illustrating the float operated lever for actuating the control valve.

Fig. 13 is a horizontal section on the line 13—13, Fig. 11.

Fig. 14 is a horizontal section on the line 14—14, Fig. 11.

Fig. 15 is a vertical section through the upper pump head taken at right angles to the section shown in Fig. 11.

Fig. 16 is a horizontal section on the line 16—16, Fig. 11 through the upper cylinder head, particularly illustrating the motor piston for controlling inlet and exhaust of the pressure medium.

Referring more in detail to the drawings:

1 designates a well or cistern containing a body of liquid 2 to be elevated under pressure of an automatic pump 3 and discharged into a delivery system 4 upon actuation of a faucet 5.

The pump 3 includes a cylinder 6 having upper and lower heads 7 and 8 closing the ends thereof to form a liquid receiving chamber 9 into which the liquid flows under hydrostatic pressure and from which the liquid is automatically displaced by a suitable pressure medium incidental to actuation of the faucet 5.

The upper head 7 includes a body portion 10 having an air inlet chamber 11 and an air inlet needle valve 12 for closing a port 13 leading from the chamber 11 to the chamber 9. The valve 12 is mounted in a cage 14 formed in the body portion 10 and includes a needle member 15 having pin and slot connection 16 with an actuating rod 17 which in turn is engaged as at 18 with one end 19 of a lever arm 20 that is pivoted on a bracket 21 fixed to the bottom face of the upper head 7. The lever arm 20, together with its function, will be more fully described later. Formed on the lower end of the body portion 10 is a disk shaped cap or flange 22 preferably of the same diameter as that of the cylinder 6 which is provided with an annular cut-out portion 23 in its lower peripheral edge for receiving the upper end of the cylinder wall 6 whereby the head is retained in concentric position relative to the cylinder, a gasket ring 24 being inserted between the cap 22 and the upper edge of the cylinder to form a pressure tight joint. Formed axially within the head 7 is a socket 25 having threads for engaging external threads of a discharge pipe 26 which depends within the cylinder 6 and has its lower end 27 threadedly engaged in a threaded opening 55

28 of a check valve housing 29 that is located in spaced relation to the bottom of the cylinder 6.

The lower head 8 includes a disk shaped cap 30 having an annular cut-out portion 31 in its upper face for receiving the lower edge of the cylinder 6 and which is sealed therewith by a packing ring 32 similar to the packing ring 24 of the upper head 7.

Connected with the cap portion 30 of the head 10 8 is a depending sleeve 33 having an axial bore 34 for passing a stud 35. The upper end of the stud 35 is threaded and engages with a threaded socket 36 of a check valve seat member 37 that is threaded into an opening 38 in the bottom of 15 the check valve housing 29.

The opposite end of the stud 35 projects from the sleeve 33 and mounts a draw-nut 39 which is screwed into bearing contact with the lower end of the sleeve 33 to draw the heads 7 and 8 into 20 sealing engagement with the ends of the cylinder 6 by means of the discharge pipe 26, check valve housing 29 and check valve seat member 37.

Formed on the nut 39 is a radially extending flange 40 having an annularly shouldered seat 41 for seating the lower edge of a cylindrical screen 42 which has its upper edge seating against a similarly annularly shouldered seat 43 formed on the cap portion 30 of the head 8. When the nut 39 is in place, the cylindrical screen is retained 30 thereby in fixed concentric alignment with the sleeve 33 to form a filter through which liquid passes before entering the pump through an annular inlet port 44.

The annular inlet port 44 extends through the cap portion of the head 8 in encircling relation to the sleeve 33, the rim portion of the head being connected with the sleeve by means of radial wings 45 bridging the port as best illustrated in Fig. 2.

40 Formed about the inner end outer peripheries of the inlet port 44 are ring like ribs 46 and 47 on the upper faces of the sleeve 33 and head 8 respectively, which form seats for a foot valve ring 48. The valve ring 48 is reciprocably 45 mounted in concentric relation with the pump cylinder on guide wings 49 extending radially from a seat member 50, the lower end of which is threadedly engaged in a socket at the upper end of the sleeve 33. Upward movement of the 50 valve ring is limited by a lateral flange 51 on the upper end of the seat member overlapping the path of travel of the ring.

It is thus apparent that when the cylinder is 55 submerged within the liquid 2, the liquid flows through the screen to unseat the foot valve 48 and fill the cylinder 6 up to a level that is controlled by a float 52 slidable upon the discharge pipe 26.

The liquid is then discharged from the cylinder 60 through the check valve housing by means of a suitable pressure medium that is delivered through a supply line 53 having its lower end connected to the air inlet chamber 11 and having its other end connected with a suitable source 65 of pressure supply, not shown, at the top of the well.

Upon admission of the pressure medium into the cylinder 6, the pressure causes seating of the foot valve 48 and displacement of the trapped 70 liquid through the check valve and pipe 26, the liquid entering the check valve housing through ports 54 that are formed within the seat member 37 and through its seat 55 upon lifting of a check valve ring 56 which normally valves off the 75 ports 54.

The check valve ring 56 is guided for reciprocation to and from its seat by a pintle 57 depending from the head of a fitting 58 that is screwed into lug 59 formed as a part of the check valve housing and having arms 60 for supporting 5 the lug 59.

Upon continued admission of the air to the cylinder 6, the liquid is forced upwardly through the pipe 26 through a by-pass port 61 in the head 7, Figs. 4 and 5, and into a delivery pipe 62 leading to the top of the cistern and connected with the supply system through a pressure chamber 63.

The pressure chamber 63 has an air dome 15 therein to provide for continuous flow of water therethrough upon variation in the pressure medium supply and particularly during the interval between the time the cylinder is filling and when the pressure medium is displacing the liquid from the cylinder as later described.

Extending through the upper side of the lug 59 is an opening 64 for mounting the lower end of a tube 65 having its upper end screwed into a boss 66 of the head 7 to communicate with a passageway 67, as best shown in Fig. 4, which leads 25 to a control cylinder 68 for the admission of pressure medium to the cylinder 6 through the air inlet chamber 11.

The lower end of the tube 65 is sealingly engaged with the opening 64 by means of a washer 39 70 encircling the projecting end of the tube and retained in seating engagement with the top of the socket 71 by the fitting 58. The fitting 58 has a recess 72 communicating with the lower end of the tube and is provided with lateral ports 35 73 leading to a lateral passageway 74 formed in the lug 59.

The passageway 74 communicates with a passageway 75 extending upwardly at right angles thereto to the top of the check valve housing; 40 the passageways 74 and 75 being formed by drilling into the check valve housing. Plugs 71 are threaded into the housing to seal the holes left by the drill.

Mounted in the upper end of the check valve 45 housing in alignment with the passage 75 is a cylindrical insert 78 which extends slightly above the top of the housing. The check valve housing is also provided with an upwardly extending bracket arm 79 for pivotally mounting a lever 50 arm 80, as at 81, which consists of a ring 82 loosely engaged about the pipe 26 in the nature of a yoke, the outer end of the lever terminating in an outwardly and downwardly curved arm 83 adapted to be engaged by the lower end of the 55 float 52 as later described.

The inner end of the lever arm is provided with a valve member 84 which consists of a housing 85 sleeveable over the insert 78 of the check valve housing and a valve head 86 mounted in 60 the housing and engageable over the upper end of the passage 75 to valve off the passageways 74 and 75. A cushion 87 is also provided to effectively seal the opening of the passage 75 together with a spring 88, the ends of which are respectively fixed to the check valve housing and lever arm for normally retaining the valve in closed position. The center portion of the spring is extended over the valve housing for normally raising the lever arm.

The float 52 previously referred to is constructed of molded material of relatively light weight to float upon the liquid admitted to the cylinder and carries a compressible bumper washer 89 on its upper end adapted to engage against a lever 75

arm when the float is in its uppermost position to actuate the lever 90 to effect operation of air inlet control valves.

When the float falls with the emptying of water from the cylinder, the lower end of the float engages the cam end 83 of the lever 80 to cause opening of the valve 84 and admission of water from the cylinder past the valve through the passageway 75 to the passageway 74 and pipe 65 to act against a piston 92, Fig. 4, in the motive power cylinder 69 of the head 7 to effect closing of the air inlet valve 12 through a lever assembly 93, now to be described.

The lever assembly 93 is clearly illustrated in Fig. 7 and consists of the bracket 21 previously described in connection with the air inlet valve that is fixed to the head 7, the yoke end 18 thereof pivotally engaging the needle valve 12 to cause its reciprocation as the lever is moved. The lever arm 20 is formed as a part of the pivoted arm 94 and extends at right angles thereto on one side of the delivery pipe 26 to a point directly beneath the motive power cylinder 69, where it is broadened as at 95, and provided with an opening 96 for the passage of an exhaust valve pin 97 which is pivoted thereto by the pin 98. The broadened portion 95 of the lever is provided with a right angularly extending arm 99 through which a bolt 99' is extended for mounting the curved lever arm 100 which extends reversely to the arm 20 on the opposite side of the pipe 26. The exhaust valve pin mounts an exhaust valve 102 (Fig. 4) engageable with the under face of the head 7 to cover the exhaust port and also mounts a piston rod 103 which is threadedly mounted on the pin and which extends through the port 104 into the motive power cylinder 69 to mount the piston 92 on a reduced threaded end 106 of the rod 103. A coil spring 107 is mounted on the rod 103 between the piston 92 and the bottom face 108 of the power cylinder to normally maintain the piston in raised position and the exhaust port closed, the piston being retained on the rod 103 by a nut 109 threaded on the threaded upper end 45 of the piston rod.

It is thus apparent that when liquid from the cylinder 6 acts against the piston 92, the piston is forced downwardly to open the exhaust port 104 and close the air inlet valve 12 through the common pivot point 110 of the valves. Then since the supply of air pressure is cut off the pressure in the cylinder may escape through the exhaust port 104 to be vented by a vent 111, formed in a plug 112 closing the top of the motive power cylinder to permit the spring to raise the piston.

In order to hold the air inlet valve 12 seated in closed position until the cylinder 6 has been refilled with liquid, I provide the head 7 with a latch mechanism 113 particularly illustrated in Figs. 2 and 3. The latch mechanism is slightly offset from the piston 92 and is in the same vertical plane as the air inlet valve and liquid outlet as shown in Figs. 6 and 7, and consists in part of a sleeve 114 mounted in the bottom face of the head 7 and has a vertically extending bore 115, which is enlarged at its lower end to form a shoulder 116 on the sleeve. The shoulder 116 is adapted for engagement by a latch pin 117 mounted on a lug 118 of the lever arm 100 eccentrically of the bolt which pivots the lever arm. When the lever 94 is in downward position the lug causes the pin 117 to be drawn inwardly due to the pivotal movement thereof to cause the pin to seat on the shoulder and thus retain the valve 12 in closed position. When the lever arm is in

upward position, the pin is forced outwardly to kick it off the shoulder, further upward movement of the lever arm 100 forcing the pin into the sleeve to permit unseating of the air inlet valve.

In order to effect automatic functioning of the valves, it is necessary to provide a pressure outlet from the cylinder 6. This is accomplished by the outlet 116' (Fig. 5) which communicates with the bottom of the motive power cylinder 69 as shown at 117' in Fig. 4 on the side of the latch mechanism opposite the piston 13, as shown in Fig. 6.

It is thus apparent that when the exhaust port is open and the inlet valve closed, pressure medium in the cylinder 6 enters the power cylinder 69 through the port 104 and seeking the line of least resistance passes along the bottom of the cylinder 69 to the outlet 116', in such a manner that pressure is relieved below the piston to permit closing of the air inlet valve 12.

In installing the equipment, the pump cylinder is submerged in the body of liquid to a sufficient depth to provide the required hydrostatic head to effect actuation of the piston 92 against the pressure medium acting on the valve 12 and also effect proper filling of the cylinder. A sufficient length of pipe 119 is connected with the exhaust port so that it will extend a suitable distance above the level of liquid carried in the well.

The line 53 supplying the pressure medium is connected with a suitable source of supply and the delivery line 62 is connected with the dispensing system 5 through the air chamber 63.

The well fluid will enter the pump cylinder through the screen 42 and lift the foot valve ring to fill the cylinder 6. Pressure medium is then turned into the line 53 which causes opening of the air inlet valve since the hydrostatic pressure of the fluid in the discharge pipe is not acting upon the piston due to the fact that the float which rises upon filling of the cylinder permits closure of the control valve 102.

Pressure medium will then flow from the valve chamber into the cylinder through the port 13 and cause seating of the foot valve and displacement of the liquid through the ports 54 to lift the check valve ring 56 for flow through the delivery pipe and to the delivery system through the pipe 26.

As the level of water recedes in the cylinder, the float drops therewith until the lower end thereof engages the cam shaped arm of the control valve lever, whereupon the control valve lever will be moved downwardly to effect opening of the control valve which allows a portion of the liquid in the cylinder to enter the passageways 75 and 74, for flow through the tube 65 to the passageway 67 to act against the piston 92 thus establishing pressure on the piston to close the air inlet valve for cutting off the supply of pressure medium, pressure in the cylinder being vented to atmosphere through the air outlet 119.

Upon relief of the pressure within the cylinder, the check valve ring 56 seats due to the static head of fluid in the delivery pipe and the foot valve 48 opens to allow a new supply of liquid to enter the cylinder from the well.

The float then again rises with the level of the liquid until the upper end thereof engages the cam of the lever 100 at the upper end of the cylinder, the control valve 85 being closed with the rising of the float to shut off pressure of the hydrostatic head of fluid acting upon the piston 92.

Pressure within the piston cylinder is relieved as explained through the vent port 111 in the piston cylinder to such an extent that the pressure medium acting against the inlet control valve 12 preponderates to cause blowing open of the valve 12 to again allow pressure medium to enter the cylinder. Upon opening of the inlet valve 12, the exhaust valve is closed both by pressure of the air and by the float pressing the lever 100 upwardly to prevent further escape of the pressure medium through the exhaust pipe.

The air will then displace the fluid collected in the cylinder in the same manner as previously described to begin another cycle of operation of the pump. These cycles will continue until the system is completely filled. During the filling of the pump cylinder the air chamber 63 will cause substantially continuous flow in the system even though the pump is intermittently operated. When the system is full and the faucet 5 is opened, the pump starts operation and when the faucet is shut off the pump ceases operation, the pressure medium being held within the cylinder until the faucet 5 is again opened.

In the form of the invention illustrated in Figs. 9 and 10, I show a modified form of control valve in the check valve housing.

In this construction the control valve 120 consists of a valve head 121 mounted in an arm 122, the head covering a passage 123 leading to a tube 124 which in turn leads to the motive power cylinder at the top of the cylinder 6. The arm 122 is mounted in fixed position by the pin 125 on the rod 126 connecting the arm 122 with a lever arm 127 similar to the lever arm 89 in the preferred form of invention with the exception that the valve end of the lever arm extends into the upper end of a compartment 128 formed integrally with the check valve housing, and pivots in the check valve housing in response to the weight of the float and upward pull of a rod 130 connected to the arm 127 as at 131 to respectively open and close the control valve 120.

It is apparent, however, that with minor alterations, for example, by eliminating the pull rod 130, the modified form of pump may be applied to the motive power cylinder illustrated in the preferred form of invention.

In the form of invention illustrated in Figs. 11 to 16, inclusive, I have provided a species of air inlet chamber 132, valve chamber 133, motive power chamber and mechanism 134, and control valve assembly 135, the remaining construction of the invention being substantially similar to that described in the preferred form of invention.

In order to prevent foreign matter of any detrimental size to pass from the air supply line 136 into the cylinder 137, the inlet chamber is equipped with a strainer 138 shown as comprising a coil spring having its upper end seated within the inlet opening of the chamber and having its lower end seated against a plug 139 closing the opposite end of the chamber.

It is thus apparent that the air is delivered from the line 136 to the interior of the spring for flow between the coils thereof which expand sufficiently to permit passage of a large quantity of air but which prevents passage of foreign matter. Upon passing the screen the pressure medium is delivered into the valve chamber 133 through a port 140 and from the valve chamber through a port in the bottom thereof into the cylinder 137 to act against the liquid collected therein.

When the cylinder has become emptied, it is necessary to shut off the air supply and to vent the cylinder to atmosphere through the valve chamber 133 which communicates with an exhaust pipe 141 having its lower end threaded into the motive power chamber 142 and its upper end extending above the level of liquid within the cistern or well.

The port 140 is provided with a valve 143 that is actuated by the motor mechanism 134 under control of the hydrostatic head of fluid flowing through the pipe 144.

The motor mechanism 134 includes an insert housing 145 having a shouldered end 146 sealingly engaged in an opening formed in the side wall of the chamber 133. The opposite end of the insert is mounted in an aligning opening formed in the side of the head in axial alignment with an exhaust chamber 149. The screw threaded cap 150 has an inwardly extending flange 151 adapted to abut against the end of the insert to retain the insert in position as shown in Fig. 11.

Formed within the insert and opening from the direction of the cap 150 is a piston cylinder 152 having its outer end communicating with a passageway 153 through notched openings 154 formed in the flange portion 151 of the cap.

Located in the opposite end of the insert is a recessed chamber 155 communicating directly with the valve chamber 133 and with the exhaust chamber 149 through radial ports 157 to form an exhaust passageway through which pressure medium is exhausted from the pump cylinder 137 to allow refill thereof as later described.

The recessed chamber 155 and cylinder 152 are separated by a diaphragm 158, Fig. 16, having an axial opening in which is slidably mounted a valve stem 159 for the valve 143 and an exhaust valve 160, the latter valve being adapted to close the exhaust port when the port 140 is opened to allow admission of pressure medium to the cylinder 137.

The valve 160 is preferably formed as a part of the valve stem or tie rod 159 extending through a cup plate which abuts against the head of the valve 143 and through a valve washer 161 which cooperates with the valve cup in retaining a compressible valve ring therebetween. Sleeved over the rod and extending through the bearing opening of the diaphragm in the insert is a sleeve 162 having one end abutting against the valve washer 161 and its opposite end against a piston 163 that is slidably mounted in the cylinder 152.

The tie rod extends through the center of the piston and has a threaded outer end for mounting a nut which is screwed thereon to clamp the piston against the end of the sleeve so that the valves and piston operate as a single unit.

It is thus obvious that when pressure is admitted to the passageway 153 it acts directly against the piston to move the piston to the left to cause closing of the valve port 140.

The effective area of the valve 143 is materially less than that of the effective area of the piston, so that the pressure of liquid acting on the piston to seat the valve need be a small amount to close the valve 143 against the high pressure medium admitted through the line 136.

In order that the piston may be moved to the right under influence of the pressure medium acting against the effective portion of the valve 143.

143, the piston is provided with a port 164 extending therethrough to the interior of the cylinder which in turn is vented to the exhaust chamber through a port 165 in the wall of the 5 cylinder.

When the supply of pressure medium is shut off from the motor, pressures on the respective sides of the piston will become equalized through flow of fluid through the port 165.

10 When the pressures approach equalization, the pressure acting against the valve 143 preponderates to cause opening of the inlet valve and seating of the exhaust valve against the seat of the exhaust port to again re-establish flow of 15 pressure medium into the pump cylinder.

In order to prevent leakage of pressure medium through the exhaust port while the valves are moving to and from seating position, the exhaust port is closed before the inlet port 20 comes effective. To accomplish this, the valve 143 carries a pilot portion 166 having sliding fit within the port 140 which retains the port closed until the valve washer 161 has entered and closed off the exhaust port.

25 Likewise, when the valves are moved in the opposite direction under influence of the liquid acting against the piston 163, the valve washer 161 prolongs full opening movement of the exhaust valve until the pilot has entered the inlet port.

30 In order to positively actuate the piston 163, I employ the hydrostatic head of fluid moving through the discharge pipe 144 which is intermittently admitted to the piston under control 35 of the float member 167 as now to be described.

The lower inlet portion 168 of the pump is similar to the preferred form of invention. A check valve housing 169 is provided, however, which has an inwardly extending lug 170 for 40 mounting a tube 171 in communicating relation to a laterally extending passage 172.

Extending at right angles to the lug 170 in parallel relation with the axis of the cylinder 137 is a bore 173 for receiving a valve housing 45 174. The valve housing 174 includes a cylindrical body having a shouldered lower end 175 seated in the bottom of the bore and extending through the lower face of the lug. The upper end of the valve housing is threadedly retained 50 in the bore and has a head 176 engaging the upper end of the check valve housing.

The valve housing is provided at its upper end with an axial bore to guidingly mount a head 55 177 of a valve 178 and at its lower end with an aligning bore 179. The valve 178 includes vertically spaced concentric bevelled annular seating surfaces 180 and 181 of differential size adapted to respectively engage seats 182 and 183 at the respective ends of the bore 179. Communicating 60 with the bore 179 between the respective valve seats are radial ports 184, Fig. 13, connected with the passageway 172 leading to the radial ports 185 within the fitting 186 of the lug 170.

65 In order to positively open and close the valve relatively to the valve seats, the head 177 is pivotally connected with an actuating lever 187 which in turn is pivotally mounted on a cross pin 188 carried by the check valve housing. The 70 opposite end of the lever is in the form of a ring 189 loosely engaging over the pipe 144 to form a yoke for connecting a pull rod 190 extending longitudinally of the pipe 144 and which terminates at the upper end of the pipe in a ring 191 slidably engaging the pipe. The outer

end of the actuating lever terminates in an arm 192 which is adapted to be engaged by the lower end of the float 167 as shown.

The operation of the form of invention illustrated in Figs. 11 to 16, inclusive, is as follows:

Assuming the cylinder 137 to be empty, the float 167 rests on the lever arm 192 to open the control valve. Liquid entering the cylinder through the foot valve is also free to enter the check valve housing and ports 185 for flow 10 through the tube 171 to act against the piston 163 to close the air inlet valve port 140.

15 Due to the differential area of the piston and valve 143, the piston will be moved to the left to effect closure of the port 140. During this movement of the valve, none of the pressure medium will escape through the exhaust valve, because the pilot 166 of the valve closes the port 140 before the valve washer 161 has opened the exhaust port.

20 At the time the valve 143 engages its seat to close the port 140, the valve washer has cleared the exhaust port to allow pressure in the cylinder to be vented to atmosphere through the ports 157 into the exhaust chamber and through the exhaust pipe 141. Upon relief of pressure within the cylinder 137, the hydrostatic head of liquid in the delivery pipe closes the check valve 193 and the foot valve 194 opens to refill the cylinder from the well.

25 The float then rises until it engages the ring 191 to lift the lever arm 189 and close the valve 178 to relieve hydrostatic pressure on the piston 163. The exhaust ports 164 and 165 relieve the piston cylinder of pressure in such a manner that pressure medium from the inlet line blows the valve 143 open to admit air to the pump cylinder, the exhaust valve closing at that time to prevent escape of pressure medium through the exhaust pipe and another cycle of operation is thus begun.

30 What I claim and desire to secure by Letters Patent is:

1. In an apparatus of the character described, a liquid receiver, liquid delivery means connected with the receiver, a source of pressure medium for supplying pressure to displace the liquid from the receiver, means for controlling admission of said pressure medium, means responsive to pressures in the receiver for actuating said control means, latch means engaged with said control means for maintaining the control means in closed condition, and means responsive to level of liquid in the receiver engageable with the latch means for permitting the control means 50 to open.

55 2. In an apparatus of the character described, a liquid receiver, liquid delivery means connected with the receiver, a source of pressure medium for supplying pressure to displace the liquid from 60 the receiver, a pressure exhaust duct connected with the receiver, means for controlling admission of said pressure medium, means for closing said exhaust duct, a piston cylinder connected with said receiver, a piston in the cylinder, a lever assembly in the receiver connecting the piston with said control and exhaust closing means, means for supplying liquid from the receiver to actuate the piston, a valve in the supply means, and a float in the receiver engageable with the lever assembly and the valve to alternately apply pressure of the liquid and pressure medium to said piston for regulating supply of said pressure medium to the receiver 70 and exhaust pressure medium from the receiver. 75

3. In an apparatus of the character described, a liquid receiving cylinder; a foot valve for admitting liquid to said cylinder; a delivery duct for discharging liquid from said cylinder; a check valve for said delivery duct; means for supplying pressure medium to said cylinder for displacing liquid therefrom through the delivery duct; an inlet valve for said pressure medium supply means; a latch for said inlet valve; an exhaust valve for said cylinder; a motive power cylinder mounted on said liquid receiving cylinder, a piston in said motive power cylinder for actuating said exhaust valve in response to pressures in said liquid receiving cylinder; a lever assembly connecting said inlet valve, latch and exhaust valve; a float in said cylinder engageable with said lever assembly to release the latch for permitting the piston to open the inlet valve and close the exhaust valve; a tube communicating with said motive power cylinder and liquid receiving cylinder; a valve for said tube; and a lever for actuating said tube valve in response to weight of the float, whereby pressure medium in the cylinder is transmitted to said motive power cylinder for acting on said piston to cooperate with said lever assembly in actuating said valve.
4. In an apparatus of the character described, a liquid receiving cylinder, a foot valve for admitting liquid to said cylinder; a delivery duct for discharging liquid from said cylinder; a check valve housing having a valve for said delivery duct; means for supplying pressure medium to said cylinder for displacing liquid therefrom through the delivery duct; an inlet valve for said pressure medium supply means; a latch for said inlet valve; a motive power cylinder mounted on said liquid receiving cylinder having an exhaust valve; a piston in said motive power cylinder for actuating said exhaust valve in response to pressures in said liquid receiving cylinder; a lever assembly in the cylinder connecting said inlet valve, latch and exhaust valve; a float in said cylinder engageable with said lever assembly for cooperating with the piston to release the latch, open the inlet valve and close the exhaust valve; a tube connecting said check valve housing and power cylinder; a valve in said check valve housing for said tube; and a lever engageable with said float for actuating said tube valve in response to weight of the float, whereby pressure medium in the cylinder is transmitted to said motive power cylinder for acting on said piston to cooperate with said lever assembly in actuating said latch and valves.
5. In an apparatus of the character described, a liquid receiving cylinder, a foot valve for admitting liquid to said cylinder; a delivery duct for discharging liquid from said cylinder; a check valve for said delivery duct; means for supplying pressure medium to said cylinder for displacing liquid therefrom through the delivery duct; an inlet valve for said pressure medium supply means; a latch for said inlet valve; an exhaust valve for said cylinder; a motive power cylinder mounted on said liquid receiving cylinder; a piston in said motive power cylinder for actuating said exhaust valve in response to pressures in said liquid receiving cylinder; a lever assembly in the liquid receiving cylinder connecting said inlet and exhaust valves and latch; and a float in said cylinder engageable with said lever assembly to release the latch for permitting the piston to actuate the inlet and exhaust valves.
6. In an apparatus of the character described,

a liquid receiving member, means for admitting liquid to said receiving member, a liquid outlet for said receiving member, interconnected pressure fluid inlet and outlet valves in the receiving member, a latch member engaged with the inlet valve normally maintaining same in closed condition, a source of pressure fluid acting on said inlet valve, and means in the receiving member movable in response to variation in level of liquid therein and engageable with the latch member for releasing the same to permit opening of the inlet valve to admit pressure fluid to the receiving member and to close said pressure fluid outlet valve for discharging liquid from said receiving member through said liquid outlet.

7. In an apparatus of the character described, liquid receiving means, means for admitting liquid to said receiving means, means for discharging liquid from said receiving means, means for supplying pressure fluid to said receiving means for displacing liquid therefrom through the discharge means, an inlet valve for admitting pressure fluid to the receiving means, a latch for said inlet valve, an exhaust valve for exhausting pressure fluid from said receiving means, a fluid motor communicating with the receiving means and controlling said exhaust and inlet valves, a lever assembly connecting said inlet and exhaust valves and latch, and means in said receiving means engageable with said lever assembly for releasing the latch to permit actuation of said valves.

8. An apparatus of the character described including a pump chamber having a valved liquid inlet and a liquid outlet, an inlet valve for admitting pressure fluid to the pump chamber, a latch for said inlet valve, an outlet valve for exhausting pressure fluid from the pump chamber, a lever member connecting said inlet and outlet valves and latch, an arm on the lever member extending below the same, and a float in the pump chamber engageable with the lever arm in response to rise in level of liquid therein and cooperable with the arm and with pressure fluid applied to the inlet valve for releasing the latch to permit opening of the inlet valve and closing of the outlet valve to discharge liquid from the pump chamber.

9. An apparatus of the character described including a pump chamber having a valved liquid inlet and a liquid outlet line, a pressure fluid inlet compartment communicating with the pump chamber, a pressure fluid inlet valve controlling communication between the inlet compartment and said pump chamber, a fluid motor cylinder, a piston slidably mounted in said cylinder having a piston rod, a pressure fluid outlet communicating with said pump chamber and motor cylinder, a pressure fluid outlet valve on the piston rod controlling communication between the pump chamber, motor cylinder and pressure fluid outlet and controlling exhaust of pressure fluid from said pump chamber, said piston rod being connected with said inlet and outlet valves and alternately maintaining the compartment and pressure fluid outlet in closed and open condition respectively relative to the pump chamber, a duct leading from the pump chamber to the fluid motor cylinder to permit pressure fluid in the pump chamber to act on said piston for actuating said valves, and means in the pump chamber controlling admission of fluid to said duct.

10. An apparatus of the character described including a pump chamber having a valved liquid inlet and a liquid outlet line, a pressure fluid inlet

- compartment communicating with the pump chamber, a pressure fluid inlet valve controlling communication between the inlet compartment and said pump chamber, a fluid motor cylinder, 5 a piston slidably mounted in said cylinder having a piston rod, a pressure fluid outlet communicating with said pump chamber and motor cylinder, a pressure fluid outlet valve on the piston rod controlling communication between the pump 10 chamber, motor cylinder and pressure fluid outlet and controlling exhaust of pressure fluid from said pump chamber, said piston rod being connected with said inlet and outlet valves and alternately maintaining the compartment and pressure 15 fluid outlet in closed and open condition respectively relative to the pump chamber, a duct leading from the pump chamber to the fluid motor cylinder to permit pressure fluid in the pump chamber to act on said piston for actuating said valves, means in the pump chamber controlling 20 admission of fluid to said duct, said duct controlling means including a valve housing in said pump chamber enclosing the lower ends of said duct and the liquid outlet line, a check valve in said housing admitting liquid to said outlet line, a valve in said housing controlling admission of pressure fluid within the housing and liquid in the outlet line to the lower end of said duct, a lever member mounted within said housing supporting 25 said duct valve and having a portion extending outwardly of said housing, and means in the pump chamber responsive to level of liquid in the chamber engageable with said outwardly extending portion of said lever member upon fall 30 of the liquid level in the chamber for opening said duct valve to permit application of fluid pressure to said motor piston.
11. An apparatus of the character described including a pump chamber having a valved liquid inlet and a liquid outlet line, a pressure fluid inlet compartment communicating with the pump chamber, a pressure fluid inlet valve controlling communication between the inlet compartment and said pump chamber, a fluid motor cylinder, a piston slidably mounted in said cylinder having a piston rod, a pressure fluid outlet communicating with said pump chamber and motor cylinder, a pressure fluid outlet valve on the piston rod controlling communication between the pump chamber, motor cylinder and pressure fluid outlet and controlling exhaust of pressure fluid from said pump chamber, said piston rod being connected with said inlet and outlet valves and alternately maintaining the compartment and pressure fluid outlet in closed 50 and open condition respectively relative to the pump chamber, a duct leading from the pump chamber to the fluid motor cylinder to permit pressure fluid in the pump chamber to act on said piston for actuating said valves, means in the pump chamber controlling admission of fluid to said duct, said duct controlling means including a check valve housing in said pump chamber enclosing the lower ends of said duct and the liquid outlet line, a check valve in said housing admitting liquid to said outlet line, a lug in said housing supporting the lower end of said duct and having a passageway therethrough, a duct valve housing in said check valve housing having a bore extending through said lug and communicating with said lug passageway, a valve slidably mounted in said bore controlling entrance of fluid to said passageway, a lever mounted exteriorly of the check valve 65 housing engaged with said duct valve, a float in said chamber engageable with said lever upon fall of level of liquid in the chamber for actuating the valve to close off said duct, and means in the chamber connected with the lever and engageable by the float upon rise of liquid level in the chamber for actuating the lever to open said duct to the passage of fluid to operate said motor piston.
12. In a compressed air pumping mechanism, the combination with a closed cylinder having an inlet for liquid, an inlet for compressed air and an outlet for exhaust air, of an inwardly opening check valve for closing said liquid inlet, a valve for closing said air inlet, a valve for closing said air outlet, means by which when either of said last named two valves opens the other closes, liquid discharge means having in the lower portion of said cylinder a liquid intake, an inwardly opening check valve for closing said liquid intake, a chamber, a piston reciprocative in said chamber and engaging and movable with said air outlet valve and, when moved in one direction, moving said air outlet valve to the open position, a liquid conductor communicating with said cylinder in the lower portion thereof and with said chamber at the end of said piston distant from said air outlet valve, whereby liquid entering said chamber through said conductor will move said piston in said direction, thus opening said air outlet valve and closing said air inlet valve, means for automatically locking said air inlet valve and said air outlet valve respectively closed and open when they are moved to said positions, a valve normally closing said conductor, and a float carried by the liquid in said cylinder and, when the liquid lowers to a predetermined level, engaging and opening said conductor closing valve, whereby liquid will pass from said cylinder through said conductor into said chamber and will move said piston in said direction, thus opening said air outlet valve and closing said air inlet valve, said float, when the liquid rises in said cylinder to a predetermined level, engaging and releasing said locking means, permitting said air inlet valve to open and said air outlet valve to close, upon which compressed air entering said cylinder through said air inlet will force liquid from said cylinder out through said discharge means.
13. In a compressed air pumping mechanism, the combination with a closed cylinder having an inlet for liquid, an inlet for compressed air and an outlet for exhaust air, of an inwardly opening check valve for closing said liquid inlet, a valve for closing said air inlet, a valve for closing said air outlet, means by which when either of said last named two valves opens the other closes, liquid discharge means having in the lower portion of said cylinder a liquid intake, an inwardly opening check valve for closing said liquid intake, a chamber, a piston reciprocative in said chamber and engaging and movable with said air outlet valve and, when moved in one direction, moving said outlet valve to the open position, a liquid conductor communicating with said cylinder in the lower portion thereof and with said chamber at the end of said piston distant from said air outlet valve, whereby liquid entering said chamber through said conductor will move said piston in said direction, thus opening said air outlet valve and closing said air inlet valve, means for automatically locking said air inlet valve and said air outlet valve respectively closed and open when they are moved to said positions, a valve normally closing said conductor,

- a float carried by the liquid in said cylinder and, when the liquid lowers to a predetermined level, engaging and opening said conductor closing valve, whereby liquid will pass from said cylinder 5 through said conductor into said chamber and will move said piston in said direction, thus opening said air outlet valve and closing said air inlet valve, said float, when the liquid rises in said cylinder to a predetermined level, engaging and 10 releasing said locking means, and means operative when said locking means is released for opening said air inlet valve and closing said air outlet valve, upon which compressed air entering said cylinder through said air inlet will force liquid from said cylinder out through said discharge means.
14. In a compressed air pumping mechanism, the combination with a closed cylinder having a liquid inlet, an inlet for compressed air and an 15 outlet for exhaust air, of an inwardly opening check valve for closing said liquid inlet, a valve which opens toward said cylinder for closing said air inlet, a valve for closing said air outlet, means by which when either of said last two 20 named valves opens the other closes, liquid discharge means having in the lower portion of said cylinder a liquid intake, an inwardly opening check valve for closing said intake, means automatically locking said air inlet valve and said 25 air outlet valve respectively closed and open when they are moved to said positions, a float carried by the liquid in said cylinder, and means operative when said float lowers to a predetermined 30 position for forcing said air outlet valve to the open position and said air inlet valve to the closed position, upon which liquid will enter said cylinder through said liquid inlet, said float, when the liquid in said cylinder rises to a predetermined 35 level, engaging and releasing said locking means, permitting said air inlet valve to open and said air outlet valve to close, upon which compressed air entering said cylinder through said air inlet will force liquid from said cylinder through said discharge means.
15. In a compressed air pumping mechanism, the combination with a closed cylinder having a liquid inlet, an inlet for compressed air and an outlet for exhaust air, of an inwardly opening 40 check valve for closing said liquid inlet, a valve which opens toward said cylinder for closing said air inlet, a valve for closing said air outlet, means by which when either of said valves opens the other closes, a float carried by the liquid in said cylinder, and a locking member which 45 automatically moves to the locking position and holds said air inlet valve closed and said air outlet valve open when said valves respectively move to said positions, said locking member being engaged and released from its locking position by said float when said float rises in said cylinder to a predetermined position.
16. In a compressed air pumping mechanism, the combination with a closed cylinder having a liquid inlet, an inlet for compressed air and an outlet for exhaust air, of a valve which opens 50 toward said cylinder for closing said air inlet, a valve for closing said air outlet, means by which when either of said valves opens the other closes, liquid discharge means having in the lower portion of said cylinder a liquid intake, a float carried by the liquid in said cylinder, and means releasable by said float when the liquid in said cylinder rises to a predetermined level for automatically locking said air inlet valve and said air outlet valve respectively in the closed and open positions when said air inlet valve and said air outlet valve are moved to said positions.
17. In a compressed air pumping mechanism, the combination with a closed cylinder having a liquid inlet, an inlet for compressed air and an outlet for exhaust air, of a valve which opens 55 toward said cylinder for closing said air inlet, a valve for closing said air outlet, means including a lever fulcrumed intermediate of and engaging said valves by which when either opens the other closes, liquid discharge means having in the lower portion of said cylinder a liquid intake, a float carried by the liquid in said cylinder, and means releasable by said float when the liquid in said cylinder rises to a predetermined level for automatically locking said lever so as to hold said air inlet valve closed and said air outlet valve open when said valves are moved to said positions.
18. In a compressed air pumping mechanism, the combination with a closed cylinder having a liquid inlet, an inlet for compressed air and an outlet for exhaust air, of a valve which opens 60 toward said cylinder for closing said air inlet, a valve for closing said air outlet, a lever connecting and fulcrumed between said valves by which when one opens the other closes, and locking means carried by said lever for automatically locking said lever, with said air inlet valve closed and said air outlet valve open, from movement when said valves respectively are moved to said positions.
19. In a compressed air pumping mechanism, the combination with a closed cylinder having a liquid inlet, a liquid outlet, an inlet for compressed air, and an outlet for exhaust air, of a valve which opens toward said cylinder for closing said air inlet, a valve for closing said air outlet, means by which when either of said valves opens the other closes, a float carried by the liquid in said cylinder, and a locking member which automatically moves to the locking position and holds said air inlet valve closed and said air outlet valve open when said valves respectively move to said positions, said locking member being engaged and released from its locking position by said float when said float rises in said cylinder to a predetermined position.
20. In a compressed air pumping mechanism, the combination with a closed cylinder having a liquid inlet, a liquid outlet, an inlet for compressed air and an outlet for exhaust air, of a valve which opens toward said cylinder for closing said air inlet, a valve for closing said air outlet, a lever connecting and fulcrumed between said valves by which when either of said valves opens the other closes, a float carried by liquid in said cylinder, and a locking member automatically movable on said lever to a locking position in which said air inlet valve will be locked closed and said air outlet valve will be locked open, said locking member being engaged and moved to a release position by said float when said float rises to a predetermined position.
21. In a compressed air pumping mechanism, the combination with a closed cylinder having a liquid inlet, a liquid outlet, an inlet for compressed air and an outlet for exhaust air, of a valve which opens toward said cylinder for closing said air inlet, a valve for closing said air outlet, means by which when either of said valves opens the other closes, a float carried by the liquid in said cylinder, and a pivoted locking member automatically movable to a locking position in

said air outlet valve respectively in the closed and open positions when said valves are moved to said positions.

17. In a compressed air pumping mechanism, the combination with a closed cylinder having a liquid inlet, an inlet for compressed air and an outlet for exhaust air, of a valve which opens toward said cylinder for closing said air inlet, a valve for closing said air outlet, means including a lever fulcrumed intermediate of and engaging said valves by which when either opens the other closes, liquid discharge means having in the lower portion of said cylinder a liquid intake, a float carried by the liquid in said cylinder, and means releasable by said float when the liquid in said cylinder rises to a predetermined level for automatically locking said lever so as to hold said air inlet valve closed and said air outlet valve open when said valves are moved to said positions.

18. In a compressed air pumping mechanism, the combination with a closed cylinder having a liquid inlet, an inlet for compressed air and an outlet for exhaust air, of a valve which opens toward said cylinder for closing said air inlet, a valve for closing said air outlet, a lever connecting and fulcrumed between said valves by which when one opens the other closes, and locking means carried by said lever for automatically locking said lever, with said air inlet valve closed and said air outlet valve open, from movement when said valves respectively are moved to said positions.

19. In a compressed air pumping mechanism, the combination with a closed cylinder having a liquid inlet, a liquid outlet, an inlet for compressed air, and an outlet for exhaust air, of a valve which opens toward said cylinder for closing said air inlet, a valve for closing said air outlet, means by which when either of said valves opens the other closes, a float carried by the liquid in said cylinder, and a locking member which automatically moves to the locking position and holds said air inlet valve closed and said air outlet valve open when said valves respectively move to said positions, said locking member being engaged and released from its locking position by said float when said float rises in said cylinder to a predetermined position.

20. In a compressed air pumping mechanism, the combination with a closed cylinder having a liquid inlet, a liquid outlet, an inlet for compressed air and an outlet for exhaust air, of a valve which opens toward said cylinder for closing said air inlet, a valve for closing said air outlet, a lever connecting and fulcrumed between said valves by which when either of said valves opens the other closes, a float carried by liquid in said cylinder, and a locking member automatically movable on said lever to a locking position in which said air inlet valve will be locked closed and said air outlet valve will be locked open, said locking member being engaged and moved to a release position by said float when said float rises to a predetermined position.

21. In a compressed air pumping mechanism, the combination with a closed cylinder having a liquid inlet, a liquid outlet, an inlet for compressed air and an outlet for exhaust air, of a valve which opens toward said cylinder for closing said air inlet, a valve for closing said air outlet, means by which when either of said valves opens the other closes, a float carried by the liquid in said cylinder, and a pivoted locking member automatically movable to a locking position in

which it will hold said air inlet valve closed and said outlet valve open when said valves respectively move to said positions, said float engaging and swinging said locking member to a release position when said float rises to a predetermined position.

22. In a compressed air pumping mechanism, the combination with a closed cylinder having a liquid inlet, a liquid outlet, an inlet for compressed air, and an outlet for exhaust air, of an inwardly opening valve for closing said air inlet, a valve for closing said air outlet, means by which when either of said valves opens the other closes, a float carried by the liquid in said cylinder, 10 a chamber, a piston reciprocative in said chamber and engaging and movable with said air outlet valve, and, when moved in one direction, moving said air outlet valve to the open position, a liquid conductor communicating with said cylinder in 15 the lower portion thereof and with said piston at the end of said piston distant from said air outlet valve, a valve normally automatically closing said conductor and engaged and moved to the open position by said float when said float lowers 20 to a predetermined position, whereby liquid will pass from said cylinder through said conductor into said chamber and will move said piston in said direction thus moving said air outlet valve to the open position and said air inlet valve to 25 the closed position, and means releasable by said 30

float on its upward movement for locking said air inlet valve closed and said air outlet valve open.

23. In a compressed air pumping mechanism, the combination with a closed cylinder having a liquid inlet, a liquid outlet, an inlet for compressed air, and an outlet for exhaust air, of two valves respectively closing said air inlet and said air outlet, means by which when either of said valves opens the other closes, a float carried by liquid in said cylinder, a chamber, a piston reciprocative in said chamber and engaging and movable with said air outlet valve, a liquid conductor communicating with the lower portion of said cylinder and with said chamber, a valve 15 normally automatically closing said conductor and engaged and moved to the open position by said float when said float lowers to a predetermined position, whereby liquid will pass from said cylinder through said conductor into said chamber and move said piston to a position in which it will open said air outlet valve and close said air inlet valve, means for moving said piston in the opposite direction so as to close said air outlet valve and open said air inlet valve, and means releasable by said float on its upward movement for locking said air inlet valve closed and said air outlet valve open.

JAMES O. McMILLAN. 30
